UNITED STATES PATENT OFFICE

WILLIAM R. STOCKWELL, OF MICHIGAN CITY, INDIANA

HEATER

Application filed August 13, 1923. Serial No. 657,198.

This invention relates to improvements in heaters.

As is well known to those skilled in the art, hand-fired heaters or boilers or furnaces of the usual construction effect about one-half of the combustion in the fuel bed and the remainder in the combustion space provided for the gases in their further travel through the heater or boiler. In this operation, the 10 solid fuel is gasified by the partial combustion of the fixed carbon and distillation of the volatile matter. The gases which arise from the fuel bed contain a relatively high percentage of combustibles, but ordinarily there 15 is no free oxygen with which to burn it. Increased air supply through the grate, as by forced draft, merely increases the rate of gasification of the fuel without changing materially the percentage of combustibles remaining in the gases which arise from the fuel bed. This results in production of smoke and 20 obviously impaired efficiency of the heater or boiler, particularly when bituminous coal is employed.

One object of my invention is to provide 25 a furnace or heater or boiler which will efficiently utilize the fuel and induce complete combustion without smoke, by introduction of supplemental air into the gases arising from the fuel bed to thereby furnish the necessary oxygen to complete the combustion.

More particularly, an object of my invention is to provide a smokeless heater or boiler 30 of the sectional type and by which the latter is rendered capable of efficiently burning bituminous or anthracite coal or coke with elimination of smoke.

A still further object of the invention is to 35 provide a heater of the character indicated which may be economically manufactured; which is simple in construction; which may be operated in the usual manner and without requiring special or skilled attention, and 40 also wherein a thorough and complete admixture of the supplemental air is insured with the gases or products of combustion arising from the fuel bed in the travel of the latter through the heater.

Other objects of the invention will more

clearly appear from the description and claims hereinafter following.

In the drawing forming a part of this specification, Figure 1 is a vertical, longitudinal, sectional view through a sectional boiler 55 showing my improvements embodied therein, the parts being broken away to better accommodate the figure on the sheet. Figure 2 is a vertical, transverse sectional view corresponding to the section line 2—2 of Figure 1 60 and illustrating more particularly the orifice employed for the introduction of the supplemental air supply.

In said drawing, the boiler shown is of the sectional type, the same consisting of a front end section A, a plurality of intermediate sections B—B, a rear section C, a special intermediate section D, next to the rear section C, and another special intermediate section E. As will be understood by those skilled in 70 the art, the number of intermediate sections B between the front section A and intermediate section E may be varied in accordance with the desired capacity of the boiler. All of the sections are preferably of the same 75 exterior contour and are mounted on a suitable base 10, the sections being provided with aligned flue passages to permit of the travel of the products of combustion, first forwardly and thence backwardly to the chimney as will 80 be understood. The front section A is provided with suitable flue doors, fuel door and slice bar door; the intermediate sections B are provided with transversely extending arched water sections 11 of T-cross-section, 85 the intermediate sections B forwardly of the intermediate section E thereby defining the roof or arch of the fire pot or fire box, the legs of the sections obviously defining the side walls of the fire chamber or box. The supporting frame 10, of rectangular outline, provides for the ash pit 12 and a series of rocker grate bars 13 are employed to form the horizontal bottom of the fire box and through which the main supply of air for the fuel is 90 admitted as customary in an updraft heater. An intermediate partition 14 is used in the supporting frame, said partition 14 extending transversely and located at the rear end 95 of the grate so as to thereby define a cham- 100

ber 15 rearwardly thereof, the latter having suitable openings 16—16 at the sides, through which air is admitted from outside of the heater.

In carrying out my invention, the rear end or wall of the fire box is defined by a vertical and transversely extending wall 17 of fire brick or other suitable heat-resisting material. Rearwardly of the said wall 17, 10 additional fire brick or other suitable heat-resisting material, as indicated at 18, may be employed, the latter having a top section 19 which extends transversely across the heater and projects over the top of the wall 17. A 15 vertical space or passageway is left between the wall 17 and the fire brick 18, said vertical passageway being indicated at 20 and having its outlet opening or orifice 21 defined by the upper edge of the wall 17 and opposed beveled under-face 22 of the overhanging section 19. Preferably the upper edge 23 of the wall 17 20 is beveled upwardly so that the orifice 21 has a general upward slope to facilitate the admission of the supplemental air, as herein- 25 after described. The front and back surfaces of the passage 20 may be lined with plates 24 and 25 and the latter suitably held apart or braced as by the staggers 26—26.

From the preceding description, considered in connection with the drawing, it will be noted that the passage 20 extends entirely across the heater so far as the effective width of the fire chamber is concerned and that the orifice 21 presents a continuous relatively 35 narrow opening for the full width of the fire chamber to thereby insure the admission of the supplemental air in a continuous sheet for the full width of the fire chamber.

The passage 20 is located centrally above 40 the partition 14 so that the supplemental air, supplied through said passage 20, may be admitted from the ash pit through the opening 27 or from the chamber 15 through the opening 28. To control the admission of the supplemental air from either the ash pit or the chamber 15, I preferably employ a pivoted flap valve 29, the pivotal axis being along 45 the upper edge of the partition 14, as clearly shown in Figure 1 of the drawing, said valve being adapted to assume either the full line 50 position shown in the drawing, under which condition the air is admitted from the chamber 15, or the dotted line position, in which case the air is admitted from the ash pit 12. Said valve or damper 29 may be controlled 55 in any suitable manner but preferably is connected by suitable chain 30 which runs over pulleys, to the main air supply door 130 to the ash pit in such manner that, when the door 130 is closed, the damper 29 will be in 60 full line position shown and, when the door 130 is open, the damper 29 will be in the dotted line position shown. In this manner, the operator cannot carelessly or intention- 65 ally shut off the supplemental supply of air

except by deliberate tampering with the mechanism.

The special intermediate section E, is provided with a transversely extending water leg or wall 31, which depends toward the fuel bed, the lower edge 32 thereof being disposed a short distance below the upper edge of the rear wall 17 of the fire box. Said water baffle wall 31 is extended across the entire width of the fire chamber and the lower edge thereof, in conjunction with the horizontal grate, defines a throat or passage through which the gases arising from the fuel must pass in their initial travel to the rear end of the heater. 70 75 80

As is well known to those skilled in the art, as the fuel on the horizontal grate is consumed, live coals from which all or most of the volatile matter has been distilled, gradually work or are worked to the rear end of the fire box and a bed of such live coals will be banked or built up against the wall 17. By extending the height of the wall 17 above the lower edge 32 of the baffle 31, I minimize the possibility of any such live coals entering or clogging the orifices 21. In the operation of the heater, it is evident that the gases arising from the fuel bed with the usual percentage of unburned combustibles, will first 85 90 95 pass through the throat or passage formed between the grate and the bottom edge of the baffle 31 and will then travel upwardly so as to pass over the section 19 between it and the water section 11 of the intermediate section B just rear of the special intermediate section E. As the gases thus travel, the supplemental supply of air is projected thereinto in a continuous sheet for the full width 100 105 110 115 120 125 130 of the fire chamber and due to the more or less swirling action which occurs in the travel of gases, a complete and thorough mixture of the supplemental air and gases will be effected, thus insuring complete burning of those unconsumed combustibles in the gases arising from the fuel bed. It will be noted that the rear wall 17 will be heated to a comparatively high temperature due to the hot coals banked thereagainst and the impinging of the gases thereagainst in their travel through the heater so that said wall 17 acts effectively, to pre-heat or superheat the supplemental supply of air before the latter is injected into the gases, as above described; thus insuring high efficiency. By properly regulating the width of the orifice 21 and the draft of the heater, the supplemental air can be injected into the gases at relatively high velocity to insure the thorough mixture desired for complete combustion.

While I have herein shown and described my invention as embodied in a sectional type of boiler of one form, nevertheless, it will be understood by those skilled in the art that my improvements may be embodied in many other forms of heaters without departing

from the spirit of the invention. All those changes and modifications are contemplated that come within the scope of the claims appended hereto.

5 I claim:

1. In a heater, the combination with a supporting base provided with an ash pit and door for admitting air to the ash pit; of a fire box for a perforate updraft grate and main air supply through the grate and from said ash pit; of a baffle wall in said fire box located near the rear end thereof and co-acting with the grate to form therewith a passage for the gases; a rear end wall beyond said baffle wall; means for delivering a supplemental air supply for admixture with said gases at a point rearwardly of said baffle wall; controllable means governing the admission of supplemental air supply from either said ash pit or from outside of the heater; and operative connections between said means and said door on the ash pit for maintaining a predetermined relation between the positions of said door and said controllable means.
2. In a heater, the combination with a fire box with a perforate updraft grate and main air supply through the grate; of a baffle wall in said fire box and located near the rear end thereof and co-acting with the grate to form therewith a passage for the gases; a rear end wall beyond said baffle wall; means for delivering a supplemental air supply for admixture with said gases at a point rearwardly of said baffle wall; and common controllable means governing the admission of the supplemental air supply from either beneath the grate or substantially directly from outside of the heater.
3. In a heater, the combination with a fire chamber defined by a perforate updraft grate, side walls, front wall, back wall and roof; of a water-containing baffle wall depending from the roof of the fire box and extending transversely of the fire box, said baffle wall being located relatively near, but forwardly of the back wall, the lower edge of said baffle wall and grate forming a passage for the gases to the rear of the fire box; means for delivering a supplemental supply of air from outside of said heater and for delivering air from beneath said grate at the back of and into the fire box at a point rearwardly of said baffle wall above the lower end thereof, said means including a common passage for said supplementary air supply; and controllable means in said passage for governing the admission of the supplemental air supply from either beneath the grate or substantially directly from outside of the heater.
4. In a heater, the combination with a fire box with a perforate updraft grate and main air supply through the grate; of a baffle wall in said fire box located near the rear end thereof and co-acting with the grate to form therewith a passage for the gases; a back end

wall subject to heat from the fuel bed and passage of the gases thereby; means for delivering a supplemental supply of air from beneath said grate or directly from the outside of said heater including a passage adjacent said back wall, whereby the supplemental air supply in its travel through said passage traverses substantially the entire rear surface of said back wall and is subject to the heat therefrom and is discharged across said passage toward said baffle wall; and controllable means for selectively governing the admission of the supplemental air supply from either beneath the grate or substantially directly from outside of the heater.

5. In a heater, the combination with a supporting base; of a partition therein dividing the same into an ash pit chamber and a supplemental chamber rearwardly thereof, the latter having openings communicating with the atmosphere; of a fire box having a bottom updraft grate over the ash pit chamber; a transversely extending baffle wall within the fire box and forming with the grate a throat for the passage of gases to the rear of the heater; a back wall rearwardly of the baffle wall; means having an air passage therein rearwardly of said back wall, said passage having an exit orifice rearwardly of the baffle wall and an intake opening extending at opposite sides of said partition; and a control damper arranged to admit the supplemental air supply to said passage from either the ash pit chamber or said supplemental chamber.

6. In a heater having a fire box provided with a main supply of air through the grate, the combination with a door controlling said main supply of air; means for introducing a supplemental supply of heated air into the fire box, said means including passages communicating with the chamber into which the main air supply is admitted and substantially directly to the atmosphere; controllable means governing the admission of the supplemental air supply through either of said passages; and operative connections between said controllable means and said door arranged to effect synchronous and predetermined movement of said controllable means and door.

In witness that I claim the foregoing I have hereunto subscribed my name this 3rd day of August 1923.
